Auguste Durand, New Westminster, British
Columbia, Canada

Application June 28, 1950, Serial No. 170,804

6 Claims. (Cl. 53—45)

1

This invention relates to machines for wrapping bundles, and particularly relatively large and bulky bundles.

There are many machines in operation for wrapping different articles, but they are such that the size of the articles to be wrapped is limited. This invention is particularly for wrapping comparatively large, bulky bundles made up of one or more articles, in an economical and efficient manner. The machine is particularly designed for wrapping bundles made up of a plurality of sheets of plywood, the dimensions of which are usually four feet by eight feet or five feet by ten feet, and is so described herein, but it is to be understood that other materials or articles formed into bundles may be wrapped. Paper is described as the wrapping material, but it is to be understood that throughout this specification and the accompanying claims, the term "paper" is intended to include any other material, such as cloth, which may be used for this purpose.

A sheet of wrapping material, such as paper, is applied to the top and bottom of the bundle to be wrapped. These sheets extend beyond the edges of the bundle so that there is sufficient material to be folded over the bundle sides and ends. The sheets may be applied by hand or automatically, and they may be pre-cut to the desired size, or the paper may be fed from rolls and cut as required. Conveying means is provided for moving the bundle and its sheets along a course, along which folding means is provided for lapping the sides of the sheets over the bundle edges as it is moved along said course, thus forming the sheets into a tube around the bundle. Suitable means is provided for securing the lapped sheet sides together. It is preferred to use an adhesive for this purpose, but staples or other fastening means may be used. When an adhesive is used, it may be applied to the appropriate surfaces of the paper during the folding operation.

At the end of this course, the bundle is ready to have the sides of the paper sheets projecting beyond its opposite ends lapped over said ends. If the bundle is substantially square in shape, it may be turned at right angles and moved by the conveying means along the same course. It is, however, preferable to provide conveying means for moving the bundle along another course. In this case, a table receives the bundle from the first course, and means is provided for tucking in the sides of the portions of the paper tube projecting beyond the opposite ends of the bundle, and directing the latter to the second conveying

means. If the bundle is rectangular in shape, the second course is located near the end of the first course and preferably extends substantially at right angles thereto so that the bundle need only be moved laterally after it has finished the first course in order to start it along the second course, along which folding means is located for lapping the other sides of the sheet over the other bundle edges as it is moved along said course.

10 These lapped sides are secured together either by an adhesive or by other fastening means, such as staples. When an adhesive is used, it is applied to the appropriate surfaces of the paper sides during the folding operation. Completely wrapped bundles are discharged from the second course.

In this wrapping operation, it is desirable to fold the side of one paper sheet over the folded sides of the other paper sheet along each edge of the bundle, but it is obvious that these folded sides may not overlap, in which case they would have to be secured to the bundle. Another possibility is the fact that this machine may be used to apply paper to the bundle and during this 25 operation, suitable fastening means, such as wire or adhesive tape, may be wound around the outside to hold the paper in place. In this case, the folded sides of the sheets need not necessarily overlap or be secured to the bundle sides.

30 One of the main objects of this invention is the provision of a machine in which bundles to be wrapped are continuously inserted in one end and come out completely wrapped at the opposite end, the entire operation being automatic.

35 An example of this invention is illustrated in the accompanying drawings, in which,

Figure 1 is a plan view of the part of the machine for feeding bundles into the main portion of the machine,

40 Figure 2 is a side elevation of the device shown in Figure 1,

Figure 3 is a plan view of the main portion of the machine, including the paper feeding and cutting apparatus, wherein the first folding operation takes place,

45 Figure 4 is a side elevation of the portion of the machine shown in Figure 3,

Figure 5 is a plan view of the portion of the machine in which the second folding operation takes place, and including the means for feeding the bundles thereto,

Figure 6 is a side elevation of the portion of the machine shown in Figure 5, with part thereof omitted,

55 Figure 7 is an enlarged section taken on the

2

line 7—7 of Figure 3 through the feed rollers and cutters,

Figure 8 is an enlarged cross section taken on the line 8—8 of Figure 3,

Figure 9 is an enlarged longitudinal section taken on the line 9—9 of Figure 5,

Figure 10 is an enlarged cross section taken on the line 10—10 of Figure 5, and

Figures 11 to 14 diagrammatically illustrate four stages of the folding operation.

The machine illustrated in these drawings includes a feeding section A, Figures 1 and 2, which directs the bundles and the sheets of paper therefor to the folding operation of the machine; a cutting section B, Figures 3 and 4, for cutting the paper into desired lengths; folding section C, Figures 3 and 4, in which the first folding operation takes place; tucking and feeding section D, in which the ends of the paper are tucked in and the bundles are directed to the next folding operation; and a folding section E, in which the second folding operation takes place.

Feeding section A

This section is illustrated in Figures 1 and 2, and it includes a frame 20 supporting a horizontal table 21 substantially midway between the top and bottom thereof. An endless conveyor 24 having transverse flights 25 thereon extends around sprockets carried by shafts 26 and 27 at the opposite ends of the table. One of these shafts is connected to a suitable source of power, as hereinafter described.

Supports 30 and 31 are provided respectively above and below the table 21, and carry one or more transverse shafts 32 and 33 upon which rolls of paper 34 and 35 are mounted. The paper rolls are in pairs, one above the other, and the rolls of each pair are of the same width, but different from the rolls of the other pairs. Each of the shafts 32 is provided with a brake 38 thereon, while each of the shafts 33 is provided with a brake 39 thereon for preventing the free rotation of their respective shafts. Stops 42 and 43 are slidably mounted on the shafts 32 and 33, each of said stops including suitable means, such as a set screw, for fixing it to the shaft. The roll of paper on each shaft is positioned thereon by these stops. If desired, the shafts may be adjustable longitudinally and vertically on their supports.

A guide bar 45 extends longitudinally of the table to one side of the conveyor 21, said bar having a stop 46 at one end thereof. This guide bar and its stop are adjustable transversely of the table. Each bundle to be wrapped, which in this example, is made of a plurality of plywood sheets, is placed on the table either manually or mechanically against the guide bar with the outer end thereof fitting against the stop 46. When the conveyor 24 is in operation, a flight 25 comes into contact with one end of the bundle and moves it longitudinally of the table. The forward end of each bundle is moved through section B of the machine and into the beginning of section C by this conveyor.

Actually there need be only one roll of paper above and one roll below the table, but it is desirable to accommodate a plurality of paper rolls of different widths in order that the machine may be quickly changed over to handle bundles of different widths.

Cutting section B

This section is clearly illustrated in Figures 75

7 and 8 of the drawings. Strips of paper 50 and 51 from the desired rolls 34 and 35 in the feeding section pass between pressure rollers of two sets of such rollers 54 and 55, and on between cutters 57 and 58. Sprockets 60 and 61, see Figure 4, are connected to one of the pressure rollers of the sets 54 and 55, and a chain 62 extends around these sprockets and around another sprocket 63 which is connected through one or more speed reduction units 64 to a motor 65. The rollers 54 and 55 are driven to draw the strips of paper 50 and 51 from the paper rolls and to direct them through the cutters 57 and 58.

The cutter 57 consists of transverse, stationary and movable cutter blades 70 and 71, respectively, while the cutter 58 consists of transverse, stationary and movable cutter blades 74 and 75, respectively. Suitable means is provided for moving the blades 57 and 58 downwardly and upwardly in vertical guides relative to their co-operating blades 70 and 74. One way of doing this is illustrated in Figures 7 and 8. A shaft 80 extends transversely of the machine beneath the cutter blades 71 and 75 at each of their opposite ends, there is a similar mechanism at each end of the shaft 80 for doing this, and as these are duplicates, one only will be described. A lever 81 is fixed to the shaft adjacent an end thereof and extends outwardly and upwardly therefrom, just off the vertical plane passing through the shaft center. The outer end of the lever is connected by a pitman 82 to the cutter blade 75 near the end thereof. Another lever 84 is fixedly mounted on the end of the shaft and projects outwardly and downwardly therefrom just off said vertical plane, but on the opposite side thereof to lever 81, see Figures 7 and 8. The outer end of this lever is connected by a pitman 85 to the lower end of a turnbuckle 86, the upper end of which is connected to the end of the cutter blade 71. When the shaft 80 is turned in an anti-clockwise direction, as seen in Figure 7, the outer end of the lever 81 moves upwardly to cause the cutter blade 75 to move in the same direction, and at the same time, the outer end of the lever 84 moves downwardly to move the cutter blade 71 in the same direction. If the outer ends of the levers 81 and 84 are moved across the vertical plane of the shaft to corresponding positions on the opposite sides thereof, the cutter blades are returned to their normal positions. When these levers are returned to their first positions, the cutter blades are again operated.

The rod 89 may be rotated in any convenient manner. For example, a lever 89 may be fixed thereto and project upwardly therefrom, the upper end of which is connected to the ram 90 of a pivotally mounted hydraulic or air operated cylinder 91. Fluid under pressure is supplied to the cylinder and controlled in any convenient manner. In this example, the fluid is air.

Folding section C

Each bundle with sheets of paper lying over the top and bottom thereof is moved along a course through this section by suitable conveying means. In this example, the folding section includes a bed 100 above which is located a support 101, said support being adjustable vertically in relation to the bed. The conveying means may consist of an endless belt 105 extending around drums 106 and 107 rotatably mounted adjacent the opposite ends of the bed, and another endless belt 110, extending around

drums 111 and 112 rotatably mounted adjacent the opposite ends of the support. One belt is directly above the other, and they are both narrower than the narrowest bundle to be moved through the machine. The adjacent runs of the belts pass over rollers 113 and 114 carried by the support 101 and bed 100, respectively. Slack 5 tighteners 115 and 116 of well-known construction may be provided for the belts 105 and 110. The conveying belts may be driven together in any convenient manner, such as by chains and 10 sprockets. In this case, sprockets 120 and 121 may be mounted on the shafts of the drums 107 and 112. An electric motor 124 rotates a shaft 125 upon which a sprocket 126 is mounted. A 15 chain 127 extends around this sprocket and around the sprocket 121, the outer surface of one side of said chain also extending around a portion of the sprocket 120, see Figure 4. A tightener 129 of known construction may be provided for this chain. With this arrangement, the motor 124 drives both of the belts 105 and 110 through the chain 127.

When a bundle with its sheets of paper over the top and bottom thereof enters the section C, it is engaged by the belts 105 and 110 to move it and the sheets as a unit through the section. As previously stated, the support 101 may be adjusted vertically to accommodate bundles of 20 different thicknesses. The sheets of paper above and below the bundle project beyond the sides thereof, and suitable means is provided in this section for folding the sides of one sheet against the corresponding bundle edges, and lapping the 25 sides of the other sheet over the folded sides of the first sheet. In this example, two folding bars 135 are located along the course over which the bundles are moved. It is preferable, although not absolutely necessary, to space these bars from the entrance end 136 of the section a distance equal at least to the length of the longest bundle to be handled. Each bar 135 lies parallel with and to one side of the conveying belts, and has a flared portion 139 at its forward end which starts substantially in a horizontal plane and twists up to the vertical plane in which the bar is located. The horizontal section of each 30 flared portion 139 lies in substantially the same plane as the upper run of the belt 105.

Following the folding bars 135, similar folding bars 142 are located on opposite sides of the conveying belts. Each of the latter folding bars is provided at its forward end with a flared portion 143 which starts in a substantially horizontal plane and twists down to the vertical plane of its bar. The horizontal section of each 45 flared portion 143 lies in substantially the same plane as the lower run of the belt 110.

An adhesive may be used for holding the folded sides of the sheet in place over the bundle edges. For this purpose, a glue pot 148 may be located on each side of the bundle course immediately after the beginning of the folding bars 135. Each glue pot has a roller 149 which may or may not be power driven, as desired.

The motor 124 drives belts 105 and 110 at exactly the same speed, and it is desirable to drive the conveyor 24 of the feeding section A at this same speed. This may be done by means of a shaft 151, see Figure 3, which is connected at one end by bevel gears 156 to the shaft 125, and at its opposite end by bevel gears 157 to a shaft 158. This shaft has a sprocket 159 on its outer end which is connected by a chain 160 to 75

a sprocket 161 mounted on the shaft 26 of the feeding section.

The support 101 may be carried by a plurality of vertical screws 165 rotatably mounted in vertical standards 166 located on opposite sides of the machine. Each screw 165 may be turned in any convenient manner to raise and lower the support. It is preferable to turn these screws by power, and one way of doing this is diagrammatically illustrated in Figures 3 and 4. A shaft 170 extends longitudinally of the section C at one side thereof, and is rotated by a motor 171 which is connected thereto by sprockets and chain 172. This shaft is connected to each screw 165 on its side of the machine through a suitable turning mechanism diagrammatically illustrated at 175. Each of these mechanisms also rotates a shaft 176 which extends across the machine to a similar mechanism for rotating a screw 165 on the other side thereof. Thus, the motor 171 may be operated to raise and lower the entire support 101. The shaft 170 may also operate a rotating mechanism diagrammatically illustrated at 179 which is adapted to lengthen or shorten the turn-buckle 86 of the cutting section B located on the same side of the machine as the shaft. This mechanism 179 may also rotate a shaft 180, see Figures 7 and 8, which extends across the machine to a similar turning mechanism on the turn-buckle on the opposite side thereof. Thus, rotation of the shaft 170 lengthens or shortens the turn-buckles 86 to allow the support 101 to move up or down in relation to the bed 100 without interfering with the operation of the cutters.

Each of the folding bars 135 and 142 is mounted on one or more slides 185 which are carried by tracks 186 extending inwardly from the side of the bed 100. Each slide has a nut 187 projecting outwardly from a side thereof. The nuts 187 of each of the folding bars on one side of the machine are aligned with similar nuts on each of the bars on the opposite side of the machine. A screw shaft 189 extends transversely of the bed through each opposed pair of nuts 187. Each shaft 189 has a left hand thread at one end and a right hand thread at its opposite end, so that when the shaft is turned, the nuts 187 thereon either move towards or away from each other. Each screw shaft 189 is connected by bevel gears 192 to a common shaft 193 extending longitudinally of the machine. This shaft may be power rotated, or it may be provided with a wheel 194 thereon by means of which it may be manually rotated. Thus, the distance between the opposed folding bars 135 and the opposed folding bars 142 may be adjusted by turning the shaft 193.

As it is desirable to shift the guide bar 45 of the section A laterally at the same time as the folding bars are shifted laterally in the section C, the shaft 193 may be continued along the section A. The guide bar 45 may be mounted on one or more slides 199 which ride on tracks 199 carried by the table 21. Each slide is provided with a nut 200 projecting outwardly therefrom through which a screw shaft 201 extends. Each shaft 201 is connected by bevel gears 202 to the shaft 193. With this arrangement, the guide bar 45 is shifted in the same direction and the same distance as the folding bars located on the same side of the machine in the section C.

Operation of sections A, B, and C

The sheets of plywood are either manually or

mechanically stacked on the table 21 of the feeding section to form a bundle. This bundle is positioned in the right place by the guide bar 45 and stop 46. When the motor 124 is started, the conveyor 24 moves until a flight 25 engages an end of the bundle and moves it towards the cutting section B. The bundle moves between the rollers of the two sets of driving rollers 54 and 55 of the cutting section towards the folding section C. As the bundle progresses, it operates an electrical switch 218 which starts the motor 65 to cause the feed rolls 54 and 55 to rotate. This feeds the strips of paper 50 and 51 to the top and bottom of the bundle. The switch is so located that the free ends of these strips extend beyond the forward edge of the bundle. This action feeds a sheet of paper to the top and bottom of the bundle and they enter the space between the belts 105 and 110 together. Each strip of paper is wider than the bundle so that portions thereof extend beyond the bundle sides. When the bundle has advanced so that it is almost completely between the conveying belts, a master switch is operated to stop the motors 124 and 65, simultaneously stopping the movement of the bundle and the paper. This master switch actually operates a time delay switch, not shown, which shuts off the motor 124 for a predetermined time. As time delay switches are well-known in electrical art, this need not be described herein. The master switch may be mounted in the section C in an appropriate position near the conveying means, or as shown, a switch 212 may be located in the section A adjacent the conveyor 24 where it is engaged at the proper time by a flight 25 of the conveyor 24. The position of this switch may be adjusted longitudinally of the section in order that it may be adjusted for bundles of different lengths.

As the bundle stops moving, the cutter blades 57 and 58 are operated to cut the strips of paper 50 and 51. The air supply to the cylinder 91 may be controlled by an electrically operated valve which is governed by an electrical switch located in section C at a suitable point which it is engaged by a bundle at the right time, or it may be positioned in section A and operated by a flight 25 in the same manner as the master switch 212.

As an alternative to this, an air valve may be located in either of the sections A or C for controlling the air supply. In this example, a ratchet-type air valve 215 for two-way operation is adjustably mounted in section A adjacent the master switch so that said valve is operated at the same time as the switch by the flight 25 moving the bundle entering the folding section. This valve is connected by pipes 216 and 217 to opposite ends of the cylinder 91, and it alternatively supplies air to the opposite ends of the cylinder to operate the cutter blades to cut off the sheets of paper lying over and under the bundle. When the valve is directing air to one cylinder end, it allows air to escape from the opposite end thereof. This type of valve is well known to the trade. The switch 212 and valve 215 are so positioned that when they are operated, the bundle is stopped and the sheets of paper cut off with portions thereof projecting beyond the rearward edge of the bundle.

After a predetermined time has elapsed, the 70 delay switch starts the motor 124 so that the bundle and its sheets are moved forwardly in the machine by the conveying belts 105 and 110. The sides of the bottom sheet of paper ride on to the flared portions 139 of the folding bars 135 75

and are turned up by said portions against the adjacent edges of the bundle. By the time the forward end of the bundle reaches the opposite ends of the folding bars, the sides of the lower sheet are completely folded against the bundle edges and retained there by the folding bars.

As soon as the sides of the lower sheets start to fold upwardly, the undersurfaces of the sides of the upper sheet ride over the rollers 149 of the glue pots 148 so that a layer of glue is applied to these sides as the sides of the lower sheets are being folded upwardly. While this folding and gluing operation is taking place, a second bundle 10 has passed through the cutting section B into the folding section C, and when this latter bundle operates the master switch, the conveying belts stop so that both bundles remain stationary. At this time the first bundle is located between the folding bars 135. When the belts start to move again, the sides of the upper sheet of paper are directed downwardly by the flared portions 143 of the folding bars 142, and the latter lap said sides over the folded sides of the bottom sheet. When the third bundle entering the section C operates the master switch, the first bundle is stopped between the folding bars 142. These press the glued sides of the paper sheets together, and the stop is sufficient to enable the glue to set to hold said folding sides together. If desired, the folding bars 142 may be provided with heating elements 220 to help set the glue. When the conveying belts start up again, the bundle is discharged from the folding section C. At this time, the sheets of paper have been folded into a tube 25 enclosing the bundle, the opposite ends of this tube projecting beyond the opposite ends of the bundle.

Tucking and feeding section D

As each bundle is discharged from the folding section C, the sides of the ends of its paper tube need to be tucked in and the tops and bottoms of said ends folded against the bundle ends. This may be accomplished by providing a table 225 at the discharge end of the folding section C, said table being provided with a plurality of transverse rollers 226, at least some of which are driven by a motor 227 through a chain drive 228, see Figure 6. A bumper 230 is mounted on the outer end of a spring-loaded, normally-extended ram 231 of an air or hydraulic cylinder 232 fixedly mounted on a block 233 movably carried by the table. This bumper lies across the path of the bundles moved by the rollers 226 along the table, the end of each bundle coming into contact with said bumper when the bundle is completely clear of the folding section C.

In this example, air is used to retract the bumper, and a flexible pipe 235 extending from a suitable source of air supply (not shown) is connected to the cylinder 232. A solenoid operated control valve 236 is located in this pipe. When this valve is opened by its solenoid, air is directed to the cylinder to retract its ram and the bumper, and when the valve is released, it permits the air to escape from the cylinder so that the bumper is returned to its normal position.

The bumper has switches 260 and 261 projecting outwardly therefrom which are engaged by the bundle as it strikes the bumper. The switch 260 at this time stops the motor 227. As it is desirable to have the powered rollers 226 rotating at the same time as the conveying means of

the first folding section, the motor 227 may be set into operation by the master switch 212.

A pusher bar 268 is movably mounted at one side of the table 225 and lies parallel with the bundles on the table after they have left the folding section. This pusher bar is reciprocated across the table by a motor 270, see Figure 5, the drive shaft 271 of which is connected thereto through gears 272 and 273, shaft 274, pinion 275 and rack 276, see Figure 9. This rack extends across the table to the pusher bar beneath the upper surfaces of the rollers 226. The pusher bar actually has a base 277 which rides on a track 278. Switch 261 on the bumper starts the motor 270 to move the pusher bar across the table, and a switch 280 mounted adjacent track 278, see Figure 9, is operated by said bar or its base 277 when the latter reaches the opposite side of the table to reverse the motor and return the bar to its normal position. Switch 281 under the normal position of the bar adjacent the track, see Figure 10, is operated by base 277 and stops the bar in its normal position. The timing of this apparatus is such that the pressure bar moves across the table and back again while the time delay switch holds the conveying means in the first folding section stationary.

When the pusher bar leaves its position, a switch 284 located beneath the normal position of the bar adjacent track 278, see Figure 10, is released by base 277 and causes the solenoid of valve 236 to open the latter to retract the bumper 230. When the pusher bar returns, switch 284 is operated to close the valve, thereby permitting the bumper to return to its normal position.

Tucker bars 290 are mounted on the pusher bar 268 at its opposite ends and project inwardly of the table 226. These tucker bars are spaced apart a distance which is just slightly greater than the length of a bundle so that when the pusher bar moves towards the bundle, these tucker bars overlap the bundle ends. The tucker bars may be moved upwards and away from each other in any convenient manner. One way of doing this is to mount each tucker bar on the outer end of a rack 292 which extends inwardly along the pusher bar and engages with a pinion 293 therein, see Figure 9, mounted on the end of a shaft 294 which projects outwardly from the bar and has a hand wheel 295 thereon. One of the racks lies over the pinion, the other rack under said pinion. When the hand wheel is turned in one direction, the tucker bars are spread apart, and when it is turned in the opposite direction, said bars are moved towards each other. The length of the pusher bar should always be less than the length of the smallest bundle to be handled by the machine.

A pair of spaced-apart, stationary tucker bars 300 are mounted adjacent the opposite side of the roller table substantially in line with the tucker bars 290. The tucker bars 300 are normally stationary, but they may be adjusted in relation to each other in the manner hereinafter described. In this example, the stationary tucker bars are located in the second folding section E.

Operation of tucking and feeding section D

The conveying means of the first folding section C directs each bundle on to the rollers 226 of the table 225 and the powered rollers move the bundle along the table towards the bumper 230. This bumper is small enough to enter the end of the paper tube around the bundle. The end of the bundle engages the switches 260 and 261 on

the bumper, the former stopping the motor 227 of the rollers, and the latter starting the pusher bar 268 across the table. As soon as the pusher bar starts to move, switch 284 operates to cause the bumper 230 to be retracted, said movement being sufficient to clear it of the paper tube. As the bar approaches the bundle, the tucker bars 290 engage the sides of the portions of the paper tube extending beyond the bundle ends and tuck said sides against said ends. Further movement of the pusher bar moves the bundle laterally of the table. In this example, the pusher bar feeds the bundle into the second folding section E. As the bundle continues to move in this direction, the tucker bars 300 engage the other sides of the ends of the paper tube projecting beyond the bundle ends and tuck these sides against the bundle end. It will be noted here that when the pusher bar reaches the end of its travel, the tucker bars 290 have moved inside the tucker bars 300 so that when the former are withdrawn, the latter retain the tucked-in portions against the bundle ends. When the pusher bar returns to its normal position, the bumper is moved outwardly to its normal position.

Folding section E

This section is very similar to the first folding section C since all that remains to be done is to lap the remaining sides of the paper sheets over the bundle ends. As said sheets are by this time formed in a tube around the bundle, it is not necessary to have an upper and lower conveyor in this section.

The section E includes a bed 309 having suitable conveying means, such as spaced endless chains 310 which extend around sprockets 311 and 312 at the opposite ends of the section. Lugs 313 are mounted on the chains for engaging the bundles to move them with the chains. The sprockets 311 are mounted on a transverse shaft 314, and the sprockets 312 on a transverse shaft 315, either of which may be rotated in any convenient manner. As it is desirable to have the conveyor 310 moving at the same time and at approximately the same speed as the conveying means of the first folding section, this conveyor may be driven by the motor 124 of said section. This may be accomplished by mounting a sprocket 320 on the shaft 125 of section C, see Figure 3, which is connected by a chain 321 to another sprocket 322 mounted on a shaft 323 which extends longitudinally of and to one side of the section E. This shaft is connected by bevelled gears 324 to the shaft 315.

Folding bars 330 having flared portions 331 at one end thereof, and folding bars 335 having flared portions 336 at one end thereof are provided on opposite sides of the course formed by the conveyor 310. The folding bars 330 and 335 correspond with and act in the same manner as the folding bars 135 and 142 of the first folding section. The folding bars of the section E are mounted for lateral movement in the same manner as the folding bars in the first folding section. It will be noted that the tucker bars 300 are substantially in line with the folding bars 330 and even overlap the flared portions 331 thereof, see Figure 6. These tucker bars are also mounted in the same manner as the folding bars and are adjusted laterally by the same mechanism.

Similarly, the block 233 of the bumper cylinder 232 is shifted longitudinally of the roller table by the same mechanism that moves the

folding bars and stationary tucker bars, see Figure 5.

Glue pots 345 having rollers 346 are mounted adjacent the folding bars 330 immediately behind the flared portions thereof. These glue pots are mounted to move with their respective folding bars. The rollers 346 may be power driven, if desired.

Operation of folding section E

In this example, the pusher bar of the tucking and feeding section D feeds the bundles into section E. This action also starts the folding operation of this section. As soon as the upper ends of the paper tube enclosing the bundle move past the tucker bars 300, the sides of the lower sheet start to be folded up by the flared portions 331 of the folding bars 330. During continued movement of each bundle, these folding bars press the said sheet sides against the bundle ends. At the same time, glue is applied to the lower surfaces of the overhanging ends of the upper paper sheet. As soon as the bundle is completely on the conveyor 310, lugs 314 thereof engage the side of the bundle to continue its movement through the section. As the bundle advances, the flared portions 336 of the folding bars 335 turn the sides of the upper sheet down over and against the folded sides of the lower sheet, and the folding bars press said sides against the bundle ends. If desired, these folding bars may be provided with heating elements 350 for applying heat to the bundle ends to help set the glue. Actually, the conveyor stops while each bundle is between the bars 335. The next movement of the conveyor discharges the bundle from the section.

Figures 11 to 14 diagrammatically illustrate a bundle in four different stages of the wrapping operation. In Figure 11, a bundle 365 has sheets of paper 366 and 367 lying over the top and bottom thereof. It will be noted that all edges of these sheets project beyond the corresponding edges of the bundle. This is the relative position of the sheets and bundle just after the sheets have been cut from the strips of paper extending from the feed rolls, and are positioned in section C ready for the first folding operation.

In Figure 12, the sides 368 of the lower sheet 367 have been folded upwardly against the bundle edges, and the sides 369 of the upper sheet 368 have had glue applied to them and have been folded over the sides 368 and pressed thereagainst. It will be clearly seen that the sheets have been folded into a tube around a bundle with the opposite ends thereof projecting beyond the bundle ends. This is the condition of the bundle and sheets when they are discharged from the folding section C.

In Figure 13, the sides 371 of the portions of the paper tube projecting beyond the bundle ends have been tucked against said ends. This took place in the tucking and feeding section D, and the bundle is fed therefrom into the second folding section E.

Figure 14 illustrates the bundle after it has passed through the folding section E. In this section, the sides 373 and 374 of the lower and upper sheets, respectively, projecting beyond the bundle ends, have been overlapped after an adhesive had been applied to the undersurfaces of the sides 374, and the latter pressed against the other sheet sides and the bundle ends to finish the wrapping operation.

What I claim as my invention is:

1. A bundle wrapping machine comprising conveying means for moving a bundle with sheets of paper over the top and bottom thereof along a course, said paper sheets extending beyond a bundle edges, folding means along the course for lapping the sides of the sheets over corresponding bundle edges as it is moved therealong to form a tube enclosing the bundle with the ends of the former projecting beyond the ends of the latter, a plurality of transverse rollers at the end of the course for receiving the bundle therefrom, a motor for rotating the rollers, a retractable bumper in line with the course positioned to be engaged by a bundle completely on the rollers, said bumper fitting into the tube of the bundle, means for retracting the bumper, a pusher bar for moving the bundle laterally from the rollers, means for moving the bar across the rollers and back to its normal position, means at the bumper engageable by the bundle to cause the bumper to be retracted and the bar to reciprocate across the rollers, conveying means extending from the rollers for receiving and moving the enclosed bundle along a second course substantially at right angles to the first course, and folding means along the second course for lapping the other sides of the sheets over the other bundle edges as it is moved along said second course.

2. A bundle wrapping machine comprising conveying means for moving a bundle with sheets of paper over the top and bottom thereof along a course, said paper sheets extending beyond the bundle edges, folding means along the course for lapping the sides of the sheets over corresponding bundle edges as it is moved therealong to form a tube enclosing the bundle with the ends of the former projecting beyond the ends of the latter, a plurality of transverse rollers at the end of the course for receiving the bundle therefrom, a motor for rotating the rollers, a retractable bumper in line with the course positioned to be engaged by a bundle completely on the rollers, said bumper fitting into the tube of the bundle, means for retracting the bumper, a pusher bar for moving the bundle laterally from the rollers, a reversible motor, driving means between the bar and the motor, a switch at the bumper engageable by the bundle to start the motor and move the bar across the rollers, another switch engaged by the bar after it has moved across the rollers to reverse the motor and return the bar to its normal position, a second switch at the bumper engageable by the bundle to cause the bumper to be retracted from its normal position, another switch operated by the returning bar to cause the bumper to move out to its normal position, conveying means extending from the rollers for receiving and moving the enclosed bundle along a second course substantially at right angles to the first course, and folding means along the second course for lapping the other sides of the sheets over the other bundle edges as it is moved along said second course.

3. A bundle wrapping machine comprising conveying means for moving a bundle with sheets of paper over the top and bottom thereof along two courses, said paper sheets extending beyond the bundle edges, folding means along one course for lapping the sides of the sheets over corresponding bundle edges as it is moved therealong, said folding operation forming the sheets into a tube around the bundle, a table for receiving the bundle from the first course, a pusher bar on the table for moving the bundle on to the conveying means of the second course, a folding bar extend-

ing along each side of the conveying means of the second course, each folding bar having a flared portion lying in a horizontal plane at the end thereof near the table and each flared portion twisting into the vertical plane of its bar, a stationary tucker bar in line with and spaced slightly from each folding bar and overlapping the flared portion thereof, and a pair of tucker bars mounted on and extending inwardly of the pusher bar, said last-mentioned tucker bars overlapping and fitting within the stationary tucker bars when the pusher bar moves the bundle on to the conveying means of the second course.

4. A bundle wrapping machine comprising conveying means for moving a bundle with sheets of paper over the top and bottom thereof along a course, said paper sheets extending beyond the bundle edges, folding means along the course for lapping the sides of the sheets over corresponding bundle edges as it is moved therealong to form a tube enclosing the bundle with the ends of the former projecting beyond the ends of the latter, a plurality of transverse rollers at the end of the course for receiving the bundle therefrom, a motor for rotating the rollers, a pusher bar for moving the bundle laterally from the rollers, means for moving the bar across the rollers and back to its normal position, conveying means extending from the rollers for receiving and moving the enclosed bundle along a second course substantially at right angles to the first course, a folding bar extending along each side of the conveying means of the second course, each folding bar having a flared portion lying in a horizontal plane at the end thereof near the table and each flared portion twisting into the vertical plane of its bar, a stationary tucker bar in line with and spaced slightly from each folding bar and overlapping the flared portion thereof, and a pair of tucker bars mounted on and extending inwardly of the pusher bar, said last-mentioned tucker bars overlapping and fitting within the stationary tucker bars when the pusher bar is moved across the rollers.

5. A bundle wrapping machine comprising conveying means for moving a bundle with sheets of paper over the top and bottom thereof along a course, said paper sheets extending beyond the

bundle edges, folding means along the course for lapping the sides of the sheets over corresponding bundle edges as it is moved therealong to form a tube enclosing the bundle with the ends of the former projecting beyond the ends of the latter, a table for receiving the bundle from said course, conveying means extending from the table for moving a bundle in its paper sheets along another course substantially at right angles to the course, a pusher bar lying substantially parallel with a bundle on the table for moving the bundle laterally from the table on to the second conveying means, means for reciprocating the bar, a bumper for stopping each bundle on the table at the same place, said bumper fitting into the tubes of the bundle, means for retracting the bumper after it is engaged by a bundle end, and means for returning the bumper to its normal position after the pusher bar has moved the bundle on to the second conveying means, spaced tucker bars projecting from the pusher bar, said tucker bars just clearing the ends of the bundle when the pusher bar moves towards the latter to tuck in the sides of the portion of the folded paper sheets projecting beyond the bundle ends, and folding means along the second course for lapping the other sides of the sheets over the other bundle edges as it is moved along said second course.

30 6. A bundle wrapping machine as claimed in claim 5 including stationary tucker bars spaced on the opposite side of the bundle from and substantially in line with the pusher bar tucker bars.
